CLAIM

We claim the ornamental design for a bird bath float, as shown and described.

DESCRIPTION

FIG. 1 is a perspective view of the bird bath float of our new design;

FIG. 2 is a front elevational view thereof;

FIG. 3 is a top plan view thereof;

FIG. 4 is a bottom plan view thereof;

FIG. 5 is a side elevational view of the left side thereof;

FIG. 6 is a side elevational view of the right side thereof;

FIG. 7 is a back elevational view thereof;

FIG. 8 is a sectional view taken along line 8—8 of FIG. 2;

FIG. 9 is a perspective view of a first modification of the bird bath float of FIG. 1;

FIG. 10 is a front elevational view of FIG. 9;

FIG. 11 is a top plan view of FIG. 9;

FIG. 12 is a bottom plan view of FIG. 9;

FIG. 13 is a side elevational view of the left side of FIG. 9;

FIG. 14 is a side elevational view of the right side of FIG. 9;

FIG. 15 is a back elevational view of FIG. 9;

FIG. 16 is a sectional view taken along line 16—16 of FIG. 10;

FIG. 17 is a perspective view of a second modification of the bird bath float of FIG. 1;

FIG. 18 is a front elevational view of FIG. 17;

FIG. 19 is a side elevational view of the right side of FIG. 17, the left side elevational view is a mirror image thereof;

FIG. 20 is a top plan view of FIG. 17;

FIG. 21 is a bottom plan view of FIG. 17;

FIG. 22 is a sectional view taken along line 22—22 of FIG. 18; and,

FIG. 23 is a back elevational view of FIG. 17.
